UNITED STATES PATENT OFFICE

MEARL E. CRAMER, OF JAMESTOWN, NEW YORK

DESIGN FOR A COMBINED TABLE LAMP AND PICTURE FRAME

Application filed November 30, 1931. Serial No. 41,918. Term of patent 7 years.

To all whom it may concern:

Be it known that I, MEARL E. CRAMER, a citizen of the United States, residing at Jamestown, in the county of Chautauqua and State of New York, have invented and produced a new, original, and ornamental Design for a Combined Table Lamp and Picture Frame, of which the following is a specification, reference being had to the accompanying drawings, forming part thereof, and in which—

Fig. 1 is a front elevation of a combined table lamp and picture frame, showing my new design;

Fig. 2 is a side elevation of the design shown in Figure 1;

Fig. 3 is a vertical sectional view, taken substantially on the line 3—3 of Figure 1; and

Fig. 4 is a plan view of the lamp, showing the contour of the base on a reduced scale.

I claim:

The ornamental design for a combined table lamp and picture frame substantially as shown.

MEARL E. CRAMER.
